DAVID J. DOLAN, OF CLEVELAND HEIGHTS, OHIO

THROTTLE CONTROL

Application filed June 8, 1931. Serial No. 542,996.

This invention relates to devices attachable to carburetors for limiting throttle-opening adjustment.

Such a device finds employment where a new automobile is to be delivered from the manufacturer to a dealer by driving the vehicle overland under its own power. It is highly essential that operation of a newly assembled vehicle be at low speeds until the parts are sufficiently "run in" to make them work freely together, and much damage will be the immediate result of overspeeding within the first few hundred miles of driving. The drivers of vehicles thus being delivered overland are of a relatively irresponsible and none too intelligent, and sometimes unscrupulous class; so that it becomes imperative that means be provided for positively preventing overspeeding during delivery.

The object of the present invention then is to provide a device which may be conveniently attached to the carburetor of a new vehicle at the factory; may be there sealed as well as secured in position to positively limit the throttle-opening adjustment, so that the speed of the engine and hence that of the vehicle is correspondingly limited; and may be as conveniently detached by the dealer or purchaser to whom the vehicle is delivered.

Experience has taught that many ingenuous expedients will be attempted to render such a device when attached, inoperative for its intended purpose, and it is the further object of this invention to make the device thoroughly protective against unauthorized tampering.

Further objects of the invention are the details of construction to this end, which are hereinafter set forth.

The exact nature of this invention together with further objects and advantages thereof will be apparent from the following description taken in connection with the accompanying drawings, in which Fig. 1 is an elevation of a carburetor mounted on the manifold which it serves, and to which the device of this invention is attachable; Fig. 2 is a corresponding view wherein the device appears

as attached; Fig. 3 is a plan view of the parts appearing in Fig. 2, taken as from the plane of line 3-3 thereof; Fig. 4 is a vertical section as in the plane of line 4-4, Fig. 3; Fig. 5 is a rear view of the principal or housing member of the device; and Fig. 6 is a horizontal section therethrough as in the plane of line 6-6, Fig. 5.

With reference now to the drawings, 1 is the lower end of the inlet manifold of an internal combustion engine which is to be served by the carburetor 2. The carburetor is mounted upon the manifold by a pair of bolts 3, one on either side of the manifold, each passing through a flange 4 at the extremity of the manifold, and into a corresponding flange 5 of the carburetor, this mounting arrangement being typical of the art. In the carburetor 2 is included the usual throttle valve 6 of butterfly type carried upon a spindle 7 upon which is secured a control lever 8 by which the valve 6 may be adjusted. Closing movement of the valve 6 is limited by a stop 9 extending from the carburetor into the path of the arm 10 of the throttle control lever, the usual screw 11 being provided whereby adjustment may be made for idling engine speed when the throttle is closed. The throttle is under operator control through the usual rod 12 associated with the lever 8 whereby the lever may be oscillated to adjust the throttle valve to its desired running position. As described, the limit of movement in closing direction is determined by the setting of the screw 11. To limit opening movement a heel 13 is provided on the lever to engage the stop 9.

It will be understood that the side of the carburetor appearing in Fig. 1 is the front side, that is, the one presented away from the engine block, which latter would be immediately behind the parts shown.

According to my invention I provide a housing adapted to be positioned against the front side of the carburetor to enclose the throttle control lever and associated parts. This housing is a generally rectangular metal casting having a front face wall 14, top and bottom walls 15 and 16, and side walls 17. The spacing between the side walls 17 is

such as to embrace the flanges 4 and 5; and the spacing between top and bottom walls 15 and 16 is such that the top wall may overlie the heads of the bolts 3 with the bottom wall 5 underlying the throttle control parts of the carburetor. The top and bottom walls have curved recesses central of their rear edges as indicated in Figs. 3 and 6 so that the top wall 15 will seat against the manifold 1 and 10 the bottom wall will similarly seat against the neck of the carburetor below the throttle. The bottom wall is cut away as at 18 on one side, as necessary to clear corresponding carburetor parts 19; and the side wall may be 15 provided with the bend indicated at 20 for the same purpose.

Thus the housing will nicely fit over the carburetor control parts to render them inaccessible. But the exact position of the housing 20 is not determined by the conformation of the walls thereof. For this purpose a socket is provided to fit over the carburetor throttle stop 9. In the exemplification shown, a socket pin 21 is riveted as at 22 in the front wall 14 of the housing, which pin is counterbored from its inner end as indicated at 23 Figs. 5 and 6 to fit over the stop 9. A plate 24 is provided in the housing to support the socket pin 21. The housing casting is provided with a projection 25 against which the plate 24 may bear and the plate is secured by a rivet pin 26 having a head 27 overlying the plate 24. The proportion and arrangement of the parts are such that when the socket pin 30 21 is positioned over the carburetor throttle stop 9, the head 27 of the pin 26 will extend into the path of the heel 13 on the throttle control lever so as to decidedly restrict opening of the throttle.

40. In order that the housing may be so positioned, an aperture 28 is provided in its side wall to clear the control rod 12.

To secure the housing in position a U-bolt 29 is provided to extend around the rear of the carburetor below the flange 5 thereof, with its ends extending forwardly through openings 30 in, and beyond, the front wall 14 of, the housing. Wing nuts 31 are turned upon the ends of the U-bolt and against the 45 front face of the housing to tightly secure the parts together. These nuts are drilled as at 32 to receive the wire 33 of a seal 34; so that once the device is attached to a carburetor, its undetected removal, which would 50 require turning of the nuts 31, is impossible.

It will be observed that the conformation of the top wall 15 of the housing provides ear portions 35 immediately overlying the heads of the bolts 3, rendering them inaccessible to 60 dismount the carburetor; so that an unauthorized substitution of carburetors cannot be made.

Obviously when the device is attached the throttle can be opened no more than to the 65 limit determined by the head 27 whose rela-

tion with the pin 21 and hence with the other control parts, is positively fixed; and the walls of the housing substantially entirely surround the throttle control parts. Likewise, these walls so surround the head 27 70 that filing or otherwise deforming the same before attachment of the device, is impossible.

What I claim is:

1. A device of the class described for attachment to a carburetor and comprising a 75 housing adapted to be positioned against the side of the carburetor to enclose the throttle control lever of the latter, and means for securing said housing in said position, said housing having a side opening to provide clearance for an actuating rod, associated with said lever.

2. A device of the class described for attachment to a carburetor, and comprising a 85 housing adapted to be positioned against the side of the carburetor to enclose the throttle control lever of the latter, and a U-bolt adapted to straddle the opposite carburetor side and be secured at its ends with the outer wall 90 of said housing.

3. A device of the class described for attachment to a carburetor bolted to an inlet manifold, said device comprising a housing adapted to be positioned against the side of the carburetor to enclose the throttle control lever of the latter, said housing having a portion adapted to overlie the heads of the carburetor-mounting bolts, and means for securing said housing so positioned whereby said bolts are inaccessible for dismounting 100 of the carburetor.

4. A device of the class described for attachment to a carburetor, and comprising a housing adapted to be positioned against the side of the carburetor to enclose the throttle 105 control lever of the latter, means in said housing cooperable with the carburetor throttle stop for locating said housing upon the carburetor, and means for securing said housing in its located position.

5. A device of the class described for attachment to a carburetor, and comprising a housing adapted to be positioned against the side of the carburetor to enclose the throttle control lever of the latter, means in said housing cooperable with the carburetor throttle stop for locating said housing upon the carburetor, and means for securing said housing in its located position, said means comprising 115 a U-bolt adapted to straddle the opposite carburetor side and be secured at its ends with the outer wall of said housing.

6. A device of the class described for attachment to a carburetor, and comprising a 125 housing adapted to be positioned against the side of the carburetor to enclose the throttle control lever of the latter, said housing having a pin adapted to project into the normal path of movement of said lever to limit the throttle opening adjustment thereof when the 130

housing is so positioned, and means for securing said housing so positioned.

7. A device of the class described for attachment to a carburetor, and comprising a housing adapted to be positioned against the side of the carburetor to enclose the throttle control lever of the latter, means in said housing cooperable with the carburetor throttle stop for locating said housing upon the carburetor, means for securing said housing in its located position, said housing having a pin adapted to project into the normal path of movement of said lever to limit the throttle opening adjustment thereof when the housing is so positioned.

In testimony whereof I hereby affix my signature.

DAVID J. DOLAN.
